UNITED STATES PATENT OFFICE

2,521,050

NUTCRACKER WITH A RECIPROCATING JAW

Robert E. Early, Wharton, Tex., assignor of one-half to Jim C. Locke, Wharton County, Tex.

Application April 4, 1949, Serial No. 85,420

1 Claim. (Cl. 146—16)

1 This invention relates to nut crackers.

An object of this invention is to provide an improved nut cracker embodying a fixed abutment or anvil against which one end of a nut is adapted to engage, and a screw shaft carrying a movable jaw or abutment for engagement with the opposite end of the nut, and including a base having a clamp for securing the device onto a table or other support.

Another object of this invention is to provide in a device of this kind, a shield extending along at least one side of the device so as to prevent undue flying of broken shells.

A further object of this invention is to provide a nut cracker embodying a screw shaft wherein the shaft is formed with triple threads so as to effect rapid endwise movement of the shaft.

With the above and other objects in view, my invention consists in the arrangement, combination and details of construction disclosed in the drawing and specification, and then more particularly pointed out in the appended claim.

In the drawing,

Figure 1 is a detail side elevation partly broken away and in section, of a nut cracker constructed according to an embodiment of this invention,

Figure 2 is a sectional view taken on the line 2—2 of Figure 1,

Figure 3 is a sectional view taken on the line 3—3 of Figure 1.

Referring to the drawing, the numeral 10 designates generally an elongated body which is adapted to be clamped to a table or other suitable support, as will be hereinafter described.

The body 10 is provided adjacent one end thereof with an upstanding lug 11 having a threaded bore 13 formed therethrough. A screw shaft 12 having a triple thread is threaded through the bore 13 and is provided at its rear end with a crank handle 14 threaded or otherwise fixed in a bushing 15 which is formed on the rear end of shaft 12.

The body 10 is provided at its forward end with a head or jaw 18 having a socket or recess 19 within which one end of a nut is adapted to engage. The body 10 is provided in the upper side thereof with a longitudinally extending and transversely arcuate channel or concave 20, and the forward end of body 10 is formed with an upstanding jaw or abutment 21 having a socket or recess 22 within which the opposite end of the nut is adapted to engage.

In order to provide a shield to prevent the pieces of shell from unduly flying away from the

2 nut cracker, I have provided an upstanding shield 23 which may be formed with one side of the body 10 having an inwardly extended arcuate surface disposed parallel to the screw shaft 12 between the nut or lug 11 and the fixed abutment or jaw 21.

The body 10 has extending from the lower side thereof an L-shaped member 24 which is formed with one side 25 thereof vertical and depending from the body 10, and the other side 26 thereof parallel with and spaced downwardly from the body 10.

A movable clamping jaw 27 is disposed between the arm or side 26 and the lower side of the body 10 and is moved toward or from the body 10 by means of a pressure applying bolt 28 having a winged head 29 fixed on the lower end thereof. The upper end of bolt 28 is rotatably mounted in a bushing 30 which is carried by the lower side of the jaw 27. The jaw 27 is of substantial length and extends toward the vertical or depending side 25 of the L-shaped member 24 and is provided with a slot 31 within which a vertically disposed bracing web 32 is adapted to loosely engage. The web 32 not only braces the L-shaped member 24 but also provides a means for holding the jaw 27 against rotation in addition to permitting sliding movement of this jaw toward or from the body 10.

In the use and operation of this device, the nut which is to be cracked is interposed between the movable jaw or head 18 and the fixed jaw or abutment 21, engaging at the opposite ends thereof in the recesses or sockets 19 and 20. The crank 14 is rotated to move the screw shaft 12 inwardly, thereby applying pressure on the nut, and effecting cracking of the shell thereof. This device may be clamped onto any table or other fixed support by means of the clamp structure embodying the movable jaw 27 and the stationary jaw or body 10.

I do not mean to confine myself to the exact details of construction herein disclosed, but claim all variations falling within the purview of the appended claim.

45 What I claim is—

A nut cracker comprising an elongated body, an upstanding lug carried by said body adjacent one end thereof and formed with a threaded bore, a second upstanding lug at the opposite end of said body, a multiple threaded screw shaft threaded through said bore, a jaw carried by said shaft confronting said second lug, said second lug having a recess confronting said jaw, a side member carried by said body extending between said lugs on one side of said body only and having an in-

wardly extended arcuate rib disposed parallel to said screw shaft, said side member integral with the body member and providing a concave for receiving the nut to be cracked, and said rib being in a plane with and transverse to the upper half of the nut receiving recess to prevent flying shell fragments, a crank fixed to said shaft, and clamping means carried by said body for securing the latter to a support.
